HINGE LUG FOR JOURNAL BOXES

Emil H. Blattner, Williamsville, N. Y., assignor to
The Symington-Gould Corporation, Depew,
N. Y., a corporation of Maryland

Application January 2, 1951, Serial No. 204,009

3 Claims. (Cl. 308—47)

1

This invention pertains to a hinge lug for use with a railway journal box.

A primary object of this invention is the provision of an improved journal box hinge lug capable of having a journal box lid pivotally associated therewith and such lid being capable of moving freely to a fully opened position.

A further object of this invention is the provision of an improved journal box hinge lug having a top surface so arranged and constructed that a journal box lid pivotally attached to the lug will be capable of moving uninterrupted and freely to an open position.

The above and many other broad objects of the invention herein contained as well as many detailed objects and features will become apparent to those skilled in the art from the succeeding description and accompanying drawings, wherein.

Figure 1 is a cross-sectional view taken through a top of a journal box embodying the present invention.

Figure 2 is a front elevational view of the improved hinge lug as considered along the lines 2—2 of Figure 1 looking in the direction of the arrows, some accessory parts being shown in section.

Figure 3 is an enlarged sectional view taken along the lines 3—3 of Figure 2 looking in the direction of the arrows.

Figure 4 is a developed curve line illustrating a progressive relationship between a bearing surface of the hinge lug, an axis of a moving lid roller and an axis of an aperture in the hinge lug.

As a preface hereto it is to be noted that a hinge lug for a railway journal box, which according to present day standards meets the requirements or with the approval of the Association of American Railways, will allow a free single swinging motion of a journal box lid to open to approximately seventy-four to ninety degrees with respect to a lid seating face of the journal box. It is highly desired, but believed to be never heretofore attained, to have the journal box lid open in one, free, uninterrupted, swinging motion to a location where an included angle between opposing faces of the lid and journal box will greatly exceed the heretofore required degree. The reason for this desire is prompted by the majority of operators who are charged with the duty of periodically inspecting the interior of the journal box, only opening the journal box lid with but a single motion which will not allow the lid to reach the required ninety degrees of

2

opening. Since this partial opening of the lid actually obstructs a full, clear and complete viewing of a journal box interior, it results in an incomplete inspection of the interior of the journal box and such incomplete inspection is, at times, tantamount to no inspection.

In addition to being capable of opening freely with one free swinging motion, the journal box lid should be capable of closing also with a single free swinging motion. This requirement, fulfilled by the structure of the present invention, is not to be accomplished with present day journal box hinge lugs as the contour thereof necessitates a sharp increase in the deflection of the lid actuating spring to pass the lid over the sharp apex of the present day hinge lug. This difficult closing has resulted in a specification calling for a relatively low pressure of the lid on the seating face of the journal box when the lid is in closed position since the rather sharp increase in pressure above mentioned builds up a force which requires considerable effort on the part of the operator to close the lid. Further, it is usual to make inspection of journal boxes on cars in a train at numerous points en route and it is essential that this work be performed as rapidly as possible so as to expedite train movement. With hard closing lids as presently in use due to the particular contour of the hinge lug, an inspector cannot perform this work expeditiously and as a result thereof some journal boxes will not be inspected with possible resulting hot boxes or other troubles due to faulty lubrication of the journal. Thus, as will be hereinafter brought out, a hinge lug of the contour of the present invention, with easy, single motion, opening and closing movements of the journal box lid, will definitely allow increasing the final closing pressure of the journal box lid against the lid seating face of the journal box and will also definitely expedite and make relatively easy the inspection of the journal box conditions at various inspection points.

With the above as a background, reference is now made to a detailed consideration of an exemplified form of the invention illustrated by the various figures of the accompanying drawings wherein like reference characters designate like parts. The numeral 1 is employed to indicate, in a somewhat general manner, a pertinent part of a journal box for use in a railway vehicle. As will be obvious to those skilled in the art to which this invention appertains, the journal box is made up in part by a roof or top wall 2 and side walls 3 only one of which is shown and these

walls have a lid seating face 4 defining an access opening 5 of the journal box. Upstanding substantially vertically from the roof adjacent to a front edge thereof is a hinge lug 6 which is disposed centrally of the journal box considered in a transverse direction. The hinge lug is formed in part by transversely spaced, hinge ears 7 which have a rounded outer surface 8 so designed and disposed that a journal box lid 9 may freely pivot about the hinge lug. The hinge ears are provided with reentrant flanges 7a which materially strengthen the hinge lug against stresses to which it will be subjected in service.

Extending between and forming an integral part of the hinge ears is a bearing block 10, with this block also being joined integrally to the roof by a neck portion 11. The hinge lug is provided with an aperture 12 which is preferably lined with a bushing 13 and a pin or pintel 14 extends entirely through the lined aperture to pivotally connect the journal box lid to the journal box. A spring pressed roller 15 is employed in the instant case to characterize a resiliently urged means incorporated in the journal box lid as a part thereof to hold the lid in either closed or open position. This illustrated roller is not to be considered as a limitation of this invention since a flat shoe, well known in the art, may also be used with the present invention. Also merely for the purpose of illustration, the lid in Figure 1 is shown pivoted to fully open position with a journal box contacting face 16 thereof at an angle of approximately one hundred and ten degrees between normally contacting faces 16 and 4.

So as to extend the service life of the journal box, the bearing block is provided with a clip 17 of relatively hard, wear-resistant material and as such presents a relatively smooth surface over which the roller may move. This clip is of a length less than the distance between the hinge ears as clearly illustrated in Figure 2 and is secured in a fixed position by the presence of welds 18 to make the clip an integral, however replaceable, part of the bearing block. It must, of course, be clearly understood that the bearing block may be provided with the illustrated clip or cast as one integral mass to include the limits of the clip; however, because of the replaceable feature of the clip it is preferred to use it, and also the clip may be manufactured to closer tolerances than would be the case of forming the bearing block as an entirely cast component.

By considering the clip as an integral part of the hinge lug the latter has a forwardly exposed, vertically disposed, front, plane surface or face 19 which extends transversely of the journal box for substantially the full length of the bearing block. This front face is in a plane substantially parallel to but, however, spaced from a vertical plane passing through an axis or center 12a of the aperture with this latter plane indicated by a diagrammatic line Z—Z in Figure 3 and which may sometimes be referred to as a vertical axis of the hinge lug. In actual practice the front face is desirably spaced from the vertical axis of the hinge lug by a distance approximating eleven-sixteenths of an inch. This latter dimension is rather important in that it is taken into consideration when calculating the holding pressure required to maintain the lid in closed position. The spring pressed roller is indicated by diagrammatic lines in Figure 3 and identified by the character 15a for a desired location of this roller when the lid is in closed position. It will be noted that the roller is at this location near the

top of the front plane face of the bearing block.

Blending in with the front face is a top or upper bearing surface or face 20 of the bearing block with the actual juncture between the front and top faces formed by an apex of relatively high curvature or small, convex, cylindrical surface 21. In actual practice this small convex surface is formed by a radius approximating three-sixteenths of an inch. It will be noted that since this small convex surface when traversed by the roller will carry the roller a greater distance away from the axis of the aperture, the apex or small convex cylindrical surface will actually function as a barrier preventing an accidental or unwarranted displacement of the roller when the lid is in closed position. This feature is brought out more clearly by referring particularly to Figure 4 where station A represents the location of the roller when the lid is in closed position—see also Figure 3—and station B represents the location of the roller when the lid is being pivoted to open position with the roller at a point farthest removed from the axis of the aperture, just as the roller is about to pass over the hump of the apex.

From the apex the top face continues rearwardly and downwardly as a relatively large, cylindrical, convex surface 22 and this surface is preferably formed as an area of rotation about a center line 23. By referring particularly to Figure 3 it will be noted that the center line 23 is below the horizontal axis of the aperture and also between the vertical axis of the aperture and front face 19 of the hinge lug as well as being in parallel relation therewith. By way of example only, it will be noted that in actual practice the large cylindrical surface approximates a distance of one inch from the center line 23. Again referring particularly to Figure 4, the curve line from station B to station C represents the effective downhill bearing area for the roller as it passes over the hump of the apex and traverses the large cylindrical surface. As will be noted, the top surface thus far considered is such that once the roller passes over the apex in an opening action of the lid, the natural tendency is for the roller to move freely in a single sweeping action because of the downhill effect caused by the particular disposition of the large convex surface.

Forming a continuation of the large convex surface is a plane terminal surface 24 directed at an incline in a downward and rearward direction to be tangential with the large convex surface. Preferably, this terminal surface of the top face is arranged normal to a plane which extends through the aperture axis and the point or line of contact of the terminal surface with the roller 15a at its maximum or full open position, and, as will be noted, a portion of this terminal surface permits the top face to approach closer to the aperture axis to continue the downhill effect of the top face. This is more clearly brought out by the developed curve of Figure 4 where it will be observed that from station C to station D the downhill effect is continued. Accordingly, therefore, in one, full, easy, undisturbed sweep, the roller, due only to the particular configuration of the top face, once it traverses the apex may move from station B to station D and at this latter station come to rest to effect a complete opening movement of the lid through an arc approximating one hundred and ten degrees.

During the closing movement of the lid the

roller will, in a single operation, be forced in what might be considered as an easy gradual up-hill sweep of the top face until the roller passes over the apex at which time the lid, through the action of the spring pressing the roller against the bearing block, will be snapped shut.

It is of particular interest to note in conclusion that it is only because of the particular disposition arrangement or relationship of the three surfaces forming the upper bearing surface or face 20 that a journal box lid is definitely capable of opening and closing in a single free swinging motion to the positions heretofore set forth.

From the above it will be noted that various changes and alterations may be made to the illustrated and described construction without departing from the spirit of this invention or scope of the appended claims.

I claim:

1. In a railway journal box, an apertured hinge lug comprising spaced hinge ears upstanding from said journal box adjacent a front edge thereof, a bearing block extending between said hinge ears, a front vertically disposed plane surface carried by said bearing block, a top face on said bearing block, said top face merging with said front surface in a small convex surface forming an apex of said bearing block, a cylindrical surface forming an intermediate part of said top face and having as a center a line located below an axis of said aperture and between parallel planes passing along said front surface and aperture axis, and said top face terminating in a plane surface tangential to said cylindrical surface, said top face beyond said apex progressively approaching said aperture axis and reaching its minimum spacing therefrom within said plane surface.

2. In a railway journal box having a lid and associated resiliently urged means, an apertured hinge lug for mounting said lid and associated means on said railway journal box, said hinge lug comprising spaced hinge ears upstanding from said journal box adjacent a front edge thereof, a bearing block extending between said hinge ears, a front vertically disposed plane surface carried by said bearing block and arranged to

contact said resiliently urged means for holding said lid in closed position, a top face on said bearing block, said top face merging with said front surface in a small convex surface forming an apex of said bearing block, a cylindrical surface forming an intermediate part of said top face and having as a center a line located below an axis of said aperture and between parallel planes passing along said front surface and aperture axis, and said top face terminating in a plane surface tangential to said cylindrical surface and arranged to contact said resiliently urged means for holding said lid in open position; said last named plane surface being substantially normal to a plane passing through said aperture axis and a point of contact of said last named surface with said resiliently urged means.

3. In a railway journal box, an apertured hinge lug comprising spaced hinge ears upstanding from said journal box adjacent the front edge thereof, a bearing block extending between said hinge ears, a wear clip replaceably secured to said bearing block, a vertically disposed plane front face on said clip, a top face on said clip and merging with said front face in a small convex surface forming an apex of said clip, a cylindrical surface forming an intermediate portion of said top face and having as a center a line located below an axis of said aperture and between parallel planes passing along said front surface and aperture axis, and said top face terminating in a plane surface tangential to said cylindrical surface, said top face beyond said apex progressively approaching said aperture axis and reaching its minimum spacing therefrom within said plane surface.
